UNITED STATES PATENT OFFICE

170,425

SUCTION SINK STOPPER

Garry J. Monahan, Jr., Bridgeport, Conn.

Application November 29, 1952, Serial No. 22,498

Term of patent 14 years

(Cl. D91—1)

To all whom it may concern:

Be it known that I, Garry J. Monahan, Jr., a citizen of the United States, residing at 1553 Central Ave., Bridgeport, in the county of Fairfield, and State of Connecticut, have invented a new, original, and ornamental Design for a Suction Sink Stopper, of which the following is a specification, reference being had to the accompanying drawing, forming part thereof.

Fig. 1 is a top view of a suction sink stopper, showing my new design,

Fig. 2 is a side view thereof,

Fig. 3 is a bottom view thereof, and

Fig. 4 is a sectional view thereof taken on line 4—4 of Fig. 1.

I claim:

The ornamental design for a suction sink stopper, substantially as shown.

GARRY J. MONAHAN, JR.
